JOHN D. McEWEN, OF PITTSBURGH, PENNSYLVANIA, ASSIGNOR TO LEE C. MOORE & COMPANY, INC., OF PITTSBURGH, PENNSYLVANIA, A CORPORATION OF PENNSYLVANIA

WALKING BEAM

Application filed September 22, 1928. Serial No. 307,567.

The invention relates to walking beams for oil well rigs.

The objects of the invention are to simplify the structure of walking beams, to provide a simple steel beam structure, to reduce the reinforcing thereof to a minimum, and to provide a connection at the driving end of the beam for a vertically reciprocable member giving a minimum of lateral movement thereof during reciprocation. Other objects will appear from the following specification.

Walking beams are usually made of heavy pieces of wood or of structural steel material, such as I-beams. It is the custom to attach the pump rod, drill rope, or the like, to the driving end of the beam by means of a bearing mounted on the top thereof. As the end of the beam moves up and down in well known see-saw motion thereof, it swings in an arc which extends above and below the horizontal position of the walking beam. There is more lateral motion of a point at the top of the end of the beam than to an opposite point at the bottom, since the beam is axially supported substantially at its middle point upon a pivotal member positioned beneath the beam. The present construction permits the bearing for the pump rod, drill rod, or the like, to be attached in approximately the level of the beam axis when the beam is in its horizontal or mid-stroke position. Consequently this arrangement gives a minimum lateral movement to the driven member during the working stroke of the beam, which is during the upward movement of the driving end.

Referring to the drawing, Fig. 1 is a partial side elevation of a walking beam and its post; Fig. 2 is a vertical cross section on the line II—II of Fig. 1; and Fig. 3 is an elevation of one end of the beam.

The walking beam comprising the present arrangement consists of a straight section of a steel H or I-beam B, having a web 1, an upper flange 2, and a lower flange 3. This beam is reinforced by a plurality of angle bars cut to a length equal to the distance between the flanges 2 and 3, and having one leg 4 of a width approximately equal to the

depth of such flanges. The angle bars are positioned with the leg 4, perpendicular to the web of the beam and bearing thereagainst. The ends of the bar bear against the inner faces of the flanges 2 and 3, the other leg 5 of the angle bar being substantially parallel to the outer edges of the flanges and extending approximately thereto. The ends of both legs of the angle bar and the inner edge of one leg are electrically welded to the beam, so that the latter is materially reinforced thereby.

At the driven end the beam is under-cut, and the web end reinforced by two or more angle bars 7 and 8. A bearing block 10 is bolted on the upper face of the beam, having a groove for receiving a loop 11 of a connecting rod 12, as will be readily understood by those familiar with the art. A locking block 13 is adapted to enclose the upper part of the loop 11 and to prevent its jumping off the beam. It will be understood that power is applied to rock the beam through the rod 12.

At the other or driving end of the beam a terminal bearing member 20 is attached, preferably by welding directly to the end of the beam. This member comprises an upper hook portion 21, which overlaps the top of the beam so as to give a positive seat thereon. It has a lower notched portion 22 which engages the lower flange of the beam. Hook-like extensions 23 have upper grooved portions for receiving the cross T of a temper screw 24. A retaining clip 25 may be attached by means of bolt 26 to hold the T-head in the seats 23.

The beam is supported by means of a saddle block 30, seating upon on axle 31, carried by brackets 32, fastened to post 33. The axle 31 comprises the axis of the beam in its operative movements. The object of the arrangement for supporting the temper screw is to bring that support as nearly as possible to the horizontal plane of the axis 31, when the beam is in horizontal position.

As will be understood by those familiar with the art the beam is driven through the rod 12 in a see-saw motion, raising and lowering the other end thereof, and consequently

driving the link member 24, to which may be attached the rope of a drill, a pump rod, or the like.

By positioning the supporting portion 23 of the bearing member 20 approximately in the level of the lower face of the beam, or below it, a minimum amount of lateral or horizontal movement of the bearing end of the loop 24 results. This brings the temper 10 screw support into the level of the axial support of the beam at mid-stroke, or horizontal beam position. This reduction of lateral movement is important, since it relieves the scraping of the drill rope against the sides 15 of the well casing, or in the case of a pump rod, minimizes the change of angularity of the rod in its packing.

The use of a straight H-beam, rolled in a single piece, is made practicable by reinforcing the web and flanges as indicated, and the welded angle irons give maximum reinforcement with minimum weight and low cost in construction.

I claim:

- 25 1. A walking beam assembly for oil well rigs comprising an H-beam section having a fulcrum pivot secured to its under side substantially midway between its two ends, a work element engaging-bearing mounted on 30 one end of the beam on the upper side thereof and another at the other end on the lower side thereof, said latter bearing element being rigidly secured to the end of the beam with its bearing surface disposed below the 35 lower edge of the beam in axial alignment with the center of said fulcrum pivot and provided with a releasable clamp for holding a work element on its bearing surface.
- 40 2. A walking beam assembly for oil well rigs comprising an H-beam section having a fulcrum pivot secured to its under side between its two ends, a bearing plate mounted on its top side at one end thereof and a substantially J-shaped bearing element rigidly 45 secured to the other end with its bearing surface in axial alignment with the center of said fulcrum pivot, said latter element having a shoulder at its upper end and a pair of spaced lugs near its lower end on the rear side thereof adapted respectively to seat on the upper flange of the beam and straddle the lower flange whereby facilitating and strengthening the attachment of said element to the beam.
- 50 55 In testimony whereof, I sign my name.
JOHN D. McEWEN.
